UNITED STATES PATENT OFFICE

2,475,639

SPRAY EVAPORATOR WITH DOME
CONDENSER

Harold Rainwater, Dayton, Wash.

Application July 5, 1944, Serial No. 543,569

2 Claims. (Cl. 202—191)

1

The present invention relates to new and useful improvements in evaporators particularly for such liquids as milk and food juices and has for the primary object to provide a device of this character comprising a unique construction and arrangement for atomizing and heating the liquid, and for condensing the vapors which rise therefrom.

Other objects of the invention are to provide an evaporator of the aforementioned character which will be comparatively simple in construction, strong, durable, highly efficient and reliable in operation, compact and which may be manufactured at low cost.

All of the foregoing and still further objects and advantages of the invention will become apparent from a study of the following specification, taken in conjunction with the accompanying drawing, wherein the figure is a vertical sectional view through an evaporator constructed in accordance with the present invention.

Referring now to the drawing in detail, it will be seen that the embodiment of the apparatus which has been illustrated comprises an insulated cylindrical tank or container 1 for the reception of a cooling fluid 2, said container including a removable cover 25. Suitable inlet and outlet pipes 23 and 24, respectively, are connected to the container 1. Mounted in the container 1 in spaced, concentric relation to the walls thereof is a dome 3. A vacuum pump 4 is connected to the top of the dome 3. On the lower portion of the dome 3 and on the inside thereof is an annular trough 5.

Mounted below the dome 3 is a heater 6. A sealing and heat insulating gasket 26 is provided between the container 1 and the heater 6. The heater 6 includes spaced inner and outer walls 7 and 8, respectively, providing a chamber 9 therebetween for the reception and circulation of a heating fluid. The heater 6 further includes a flat bottom plate 10. Fluid inlet and outlet pipes 11 and 12, respectively, communicate with the jacket or chamber 9.

Mounted vertically in the heater 6 is a perforated injection pipe 13. A supply pipe 14 from a high pressure injection pump 15 is connected to the pipe 13. The supply pipe 14 passes through a suitable preheater 16.

Connected to the bottom of the heater 6 is an outlet pipe 17. An ejector pump 18 is connected to the outlet pipe 17. The pipe 17 passes through a cooling jacket 19. An ejector pump 20 is connected by a pipe 21 to the trough 5 to remove the vapor condensed to a liquid.

It is believed that the operation of the device

2

will be readily apparent from a consideration of the foregoing. Briefly, the liquid, under high pressure from the pump 15 is heated by the preheater 16 as it flows through the supply pipe 14 to the horizontally perforated injection pipe 13. The warm vapor from the atomized liquid from the injection pipe 13 partly rises to condense on the cold walls of the dome 3 and gravitates to the trough 5, from which it is taken off through the pipe 21 by the ejector pump 20. Some of the atomized liquid from the pipe 13 strikes the heated walls 7 of the heater 6 where a portion of it vaporizes and rises to condense on the walls of the dome 3. The thicker or uncondensed liquid from the pipe 13 gravitates to the bottom of the heater 7 where it is taken off through the pipe 17 by the pump 18 and cooled by the jacket 19. Part of the atomized liquid from the injection pipe 13 strikes the hot inner wall 7 of the heater 6 and 10 gravitates to the bottom of said hopper where it is taken off through the pipe 17 and the pump 18. Vapors which rise from the liquid contact the dome 3 and are condensed thereon. The condensate runs down the walls of the dome 3 into the trough 5 where it is taken off through the pipe 21 and the pump 20. The outer wall 8 of the heater 6 is insulated, as at 22.

For the purpose of this specification and claims, the words and expressions: "pipe," "tube," "tubular," "tubular member" are deemed to be synonyms.

It is to be noted that my novel evaporator produces two principal products. One of them is collected in the trough 5 while the other is taken from the bottom of the heater 6 and cooled by the cooler associated with pipe 17.

It is believed that the many advantages of an evaporator constructed in accordance with the present invention will be readily understood and although a preferred embodiment of the device is as illustrated and described, it is to be understood that changes in the details of construction, and in the combination and arrangement of parts may be resorted to which will fall within the scope of the invention as claimed.

What is claimed is:

1. An evaporator comprising a heat-insulated tank for holding a liquid coolant and having inlet and outlet means, a dome having its top closed and its bottom open and arranged in the tank, a trough within the open bottom of the dome, a downwardly tapered heater shell having an upper open end disposed inwardly of and adjacent to the trough, a jacket for the heater shell for receiving a heating fluid, a vertical injector pipe

passing through the bottom of the heater shell and having its top terminating near the elevation of the top of the heater shell, said pipe having apertures which spray a liquid feed horizontally upon the inner face of the heater shell throughout substantially the entire vertical dimension of such face, means to preheat the liquid feed and supply it under pressure to the vertical pipe, means including a pipe to withdraw the liquid feed from the bottom of the heater shell, and 10 means to withdraw the condensate from the trough including a pipe, and a suction device including a pipe connected with the top of the dome.

2. An evaporator comprising a heat-insulated tank for holding a liquid coolant and having inlet and outlet means, a dome having its top closed and its bottom open and arranged in the tank, a suction device including a pipe connected with the closed top of the dome, a trough within the 20 open bottom of the dome, a heater shell having an upper open end disposed inwardly of and adjacent to the trough, a jacket for the heater shell for receiving a heating fluid, a vertical injector pipe passing through the bottom of the heater shell and having its top terminating near the elevation of the top of the heater shell, said pipe

5 having apertures which spray a liquid horizontally upon the inner face of the heater shell throughout substantially the entire vertical dimension of such face, means connected with the vertical pipe to supply the liquid feed under pressure to the vertical pipe, and pump means to withdraw the liquid feed from the bottom of the heater shell and the condensate from the trough.
